UNITED STATES PATENT OFFICE.

WILLIAM H. AVERILL, OF DORCHESTER, MASSACHUSETTS, ASSIGNOR TO UNITED DRUG CO., OF BOSTON, MASSACHUSETTS.

DISPLAY DEVICE.

Application filed November 5, 1924. Serial No. 747,978.

This invention relates to display devices and with regard to certain more specific features thereof to a collapsible frame adapted to be set up in the form of an easel to display boxes. It is more particularly adapted to display boxes such as are in common use for confectionery having a cover which is entirely removable from the box.

The invention has for one of its objects to provide a very inexpensive and reliably effective easel for displaying not only the contents of the box, but the cover as well. This enables the merchant to convey to the public an impression of the confections or other merchandise contained in the box, and also an idea of the package as it will be purchased with cover design, trade-marks, manufacturer's name, and descriptions of the quality, weight and material of the box.

Another object of the invention is to provide a display device of the character above mentioned which may be easily collapsed for purposes of transportation and storage, and which may be as easily re-arranged into the form of an easel supporting a box with contents exposed to view, but protected from dust and arranged in highly sanitary form.

In the drawings wherein is shown one of the various possible forms of the invention.—

Figure 1 is a view in perspective of the improved display frame set up to hold a box, but with the box cover eliminated from the view in order to show the construction of that part of the frame which holds the cover.

Figure 2 is a perspective view looking towards the rear of the frame.

Figure 3 is a sectional view of the display frame in collapsed condition.

Referring now more particularly to the drawings, a front or face frame 10 is composed of a wire 11 bent in inverted U-shape with the lower legs of the inverted U bent back upon themselves to form rails 12, one on either side of the frame. These rails are carried upwardly a little over half way and soldered as indicated at point 13. At the extreme lower end of the inverted U frame 11 the legs of the U are connected by a transverse strip 14 of thin sheet metal, the opposite ends of the strip being folded around the wire 11, and the upper and lower edges of the strip 14 being formed as indicated in

Figure 3 of the drawings at 15 and 16 respectively. The turned in edge 16 serves to strengthen the transverse strip 14 and provide a suitable contact edge for the display frame when in position at a table or counter. The formation of the upper edge of the transverse strip 14 as indicated at 15 is of channel shape to receive the glass window 17 arranged and secured in position as indicated in Figures 1 and 3, by thin metal strips 18, 19 and 20. These strips serve to provide a sub-frame which is designed to the proper size of the box which it is intended to display. This construction leaves above the sub-frame a loop of the wire 11 of proper size to receive the box cover as indicated in Figure 2 at 21.

The rear frame 22 is formed out of small round wire, and opposite ends of this frame are loosely connected to the front face frame 10 as indicated at 23 in Figures 1 and 2 of the drawings. This frame is of bail-like form with inwardly projecting portions 24 which are adapted to take in behind a box 25 arranged beneath the window of the front frame.

The assembly is made by presenting the box 25 to the rear of the front face frame opposite the window. The rear frame 22 is then moved from its collapsed position as indicated in Figure 3, along the rails 12 until suitable engagement is made of the inwardly projecting members 24 with the base of the box 25. This assembly will cause the frame to stand easel fashion supported along a line of contact with the turned edge 16 of transverse strip 14 of the front frame and a transversely extending portion 30 of the rear frame. The box having been introduced and the assembly set up in "stare" fashion, the box cover may be passed in to the loop which is formed by the upper U-shaped section of the front frame. The device is particularly suitable for boxes with flanged covers inasmuch as the flange of the box obscures the wire of the front frame.

Having described the invention, what I claim as new and desire to secure by Letters Patent is:

1. A collapsible display device comprising a front face frame and a rear movable frame joined to receive a box and co-act with said box to form an easel and display

the box, said front face frame having an upper loop to receive and retain the box cover in display above the box.

2. A display frame comprising a front face frame and a rear frame joined therewith so as to be movable therealong to assume different positions, the rear frame having inwardly extending portions adapted to take in under a box inserted between the two frames and thereby cause the box and frame to stand easel fashion, and the front frame having means for receiving and retaining a separate box cover.

3. A display frame comprising a front face frame and a rear frame joined therewith so as to be movable therealong to assume different positions, the front frame having a lower cross strip adapted to serve as an inscription plate, a window above the strip and a means above the window to receive and hold a box cover, the rear frame having means for receiving a box between it and the window portion of the front frame.

25 4. In a device of the character described, in combination, a front frame comprising a large loop divided into an upper open loop section and a lower window section, said frame having side rails, a rear frame con-

nected to the front frame at the side rails 30 and adapted to be moved along said rails into different positions at an angle to the front frame until the upper ends of the rails are reached and the rear frame may be swung into substantially parallel relation with the front frame.

5. In a collapsible display device, in combination, a front face frame comprising a rectangular loop having a lower frame with a transparent shield, and a rear supporting frame, slidable up and down the lower frame of the loop and having an inwardly bent portion to take under a box positioned against the shield, the connection between the front and rear frames providing for a pivotal movement of the rear frame at any position assumed in the sliding movement thereof on the loop.

6. A display frame for a box and deep cover, comprising a loop frame with lower 50 portion provided with a transparent shield, means for holding a box in stare fashion against the back of the shield, the loop frame extending sufficiently beyond to bodily receive the cover of the box and 55 bound its edges thereby holding it adjacent the box.
